UNITED STATES PATENT OFFICE

CHARLES H. FRANZ, JR., OF MILWAUKEE, WISCONSIN

LOOSE-LEAF BINDER

Application filed December 9, 1929. Serial No. 412,863.

This invention relates to improvements in loose-leaf binders.

One of the objects of this invention is the provision of a comparatively cheap form of loose-leaf binder provided with novel fastening means which cooperates directly with the locking pins, whereby one of the covers can be unlocked from the pins and moved to an open flat position with respect to the other cover and the movable cover can be quickly arranged in position and secured to the locking pins.

Another object of the invention is the provision of a loose-leaf binder of the above type wherein the locking pins are adjustable so that the two cover members may be positioned at different distances from each other to accommodate a small number of sheets between the cover, or a large number, as the case may require.

A further object of the invention is the provision of a loose-leaf binder wherein one of the cover portions can be easily moved to a flat position when opened and carries novel securing means adapted to cooperate with adjustable locking pins carried by the other cover section whereby the binder may be quickly opened to permit the insertion of additional sheets between the covers, or may be quickly moved and closed to a locked position.

With the above and other objects in view, the invention consists in the novel features of construction, the combination and arrangement of parts hereinafter more fully set forth, pointed out in the claim and shown in the accompanying drawing wherein:

Figure 1 is a transverse sectional view taken through my improved loose-leaf binder;

Figure 2 is a section on the line 2—2 of Figure 1; and

Figure 3 is a detail section on the line 3—3 of Figure 1.

Referring more particularly to the drawing, it will be noted that my improved binder comprises the cover members 1 and 2, integrally joined by a flexible portion 3. The forward edges of the covers 1 and 2 are folded inwardly upon themselves, as shown at 4,

and is securely maintained in this position by means of a thin lining layer 5, secured to the inner faces of the cover members 1 and 2 by any suitable type of adhesive with the forward edges of this lining extending over the inwardly folded edge of each cover for retaining the folded edges of the cover in position.

The integral connecting part 3 is provided with a lining portion 6 one edge of which is adapted to be folded around a metal reinforcing strip 7, and then folded under the inner edge of the lining layer 5, as shown in Figure 1, with the edge of the lining 6 securely fastened to the reinforcing strip 7 by a suitable adhesive, and also secured to the layer 5 as well as the cover portion 2 by an adhesive. The reinforcing strip 7 carries the upstanding guide pins 8 which are adapted to cooperate with the downwardly projecting guide pins 9 carried by the transfer strip 7'.

The other edge of the lining piece 6 is folded around the reinforcing strip 10 and thence extends upwardly with its extreme portion positioned between the inner edge of the layer 5 and cover 1, as shown at 12, and is secured to these two parts by any suitable type of adhesive.

In connecting the upper edge of the lining part 6, the folded portion is sufficiently long to provide a flexible hinged part 13 which is disposed between the reinforcing strip 10 and the flexible part 3. Arranged above the reinforcing strip 10 and positioned on top of the portion of the lining which extends across the upper face of the strip 10 is the strip 11, and the metal strips 10 and 11 with the associated portion of the lining 6 are secured together by means of the eyelets 14.

Attached to each end of the strip 7 are the internally threaded tubular parts 15 in which are the adjustably mounted locking pins 16. The upper ends of these pins are provided with an annular groove 17 forming a restricted portion on each pin, and it will be noted from the illustration in Figure 2, that the ends of the reinforcing strip 11 are provided with transverse notches 18 adapted to receive the restricted portion of the locking pins 16.

pins so that a portion of each end of the strip 11 can be positioned beneath the head 19 on each locking pin.

In order to lock the ends of the strip 11 to the adjustable pins 16, a slidable plate 20 is mounted at each end of strip 11 and each plate is formed with a slot 21 and positioned within the slots 21 are the barrel portions of the eyelets 22 and 22' carried by the reinforcing strips 10 and 11, said eyelets limiting the movement of the locking plate 20 in either direction. The outer end of the locking plate is bifurcated to form two spaced fingers 23 which are adapted to fit upon opposite sides of the head 19 of pin 16 for maintaining the ends of strip 11 in engagement with the restricted portions of the pins.

The strip 11 is provided adjacent each end with depressions from the lower side which form outstanding teats 24 which, as will be noted in Figure 3, form suitable stops for the locking plates 20 when the same are in operative position, as shown in Figure 3, but will permit the plates to be moved to an unlocked position by engaging a finger of the hand with the transverse slot 25 formed in the inner end of each locking plate.

It will be apparent from the foregoing that when the two cover portions 1 and 2 are in closed position, the ends of the strip 11 will be engaged with the restricted portion of the locking pins 16 and will be maintained in this position by moving the locking plates 20 outwardly so that the fingers 23 will be positioned upon opposite sides of the upper slot of the locking plate.

However, when it is desired to release cover 1, the plates 20 can be moved inwardly so that the ends of strip 11 may be disconnected from the locking pins 16, thus entirely releasing cover 1 from any other adjacent parts of the binder so that the cover 1 can swing to an open position and lie flat on a surface in the same plane as cover 2, and as the reinforcing strips 10 and 11 and the parts carried thereby are supported by the hinged connection 13 of the lining strip 6, the cover 1 can be readily moved to a closed position and strip 11 readily positioned for having its ends engaged with the locking pins 16, after which the locking plates 20 can again be moved outwardly to a locking position, as shown in Figure 2.

In view of the fact that the pins 16 are adjustably mounted in the tubular portions 15 and guide pins 8 and 9 have their inner ends extending a considerable distance beyond each other, a great many sheets may be positioned upon the guide pins and carried between the covers 1 and 2.

While I have shown and described the preferred embodiment of my invention, it will be apparent that slight changes may be made in the construction when putting the invention into practice without depart-

ing from the spirit of the same or the scope of the appended claim.

I claim:

A loose leaf binder comprising opposed cover members, a flexible back portion joining said cover members, attaching members connected with said cover members, internally threaded tubes carried by the ends of one of said attaching members, a lock strip secured to the other attaching member and projecting beyond the ends thereof, locking pins adjustably engaging said tubes having enlarged heads formed thereon provided with annular grooves, a transverse strip removably fitted over said locking pins, leaf guide pins carried by the attaching member having the tubes and said transverse strip, said guide pins being arranged in staggered relation and between the locking pins and tubes, the lock strip having transverse notches therein at its terminals for engaging in the grooves on the heads of the locking pins, and locking plates slidably carried by said lock strip having notches arranged at right-angles to the first-mentioned notches removably engaging said locking pins and cooperating with said first notches holding the locking pins against sliding movement relative to the lock strip.

In testimony that I claim the foregoing I have hereunto set my hand at Milwaukee, in the county of Milwaukee, and State of Wisconsin.
